SHUTTLE CONTROL FOR SHUTTLE
CHANGING LOOMS

Richard Greenleaf Turner, Worcester, Mass., as-
signor to Crompton & Knowles Loom Works,
Worcester, Mass., a corporation of Massachu-
setts

Application September 13, 1933, Serial No. 689,209
Renewed April 17, 1936

8 Claims. (Cl. 139—232)

This is a continuation in part of a portion of the disclosure in my prior co-pending application Serial No. 460,746.

In multicolor shuttle changing looms it is convenient to arrange the stacks of reserve shuttles in one magazine with a common delivery throat or compartment through which the reserve shuttles of the different stacks move during or preparatory to the shuttle changing operation.

10 In the form of invention set forth in the aforesaid application I show front and back cells or stacks with the common compartment located under the front cell and in front of the lowest shuttle in the back cell. The latter shuttle is forced positively into the compartment and slides along a supporting platform, being guided by clips or the like which extend around the ends of the shuttle to prevent it from rotating on its axis. The bottom shuttle of the front cell is required to fall through a distance somewhat greater than its own height, and there is an opportunity for it to rotate, in which case it may reach the compartment on its side instead of the bottom.

25 In order to prevent this undesired rotation of the front reserve shuttles I provide means for advancing the bottom shuttle of the rear stack so that the front wall thereof will lie practically in the same plane as the rear wall of the descending front shuttle, mutual engagement of the shuttles preventing rotation. It is an important object of my present invention to provide means for locating the bottom shuttle of the rear stack so that it will accomplish this result.

30 35 When the rear cell is empty, there is no engagement such as just described, and it is a further important object of my invention to provide means which will in effect perform the function of the front wall of the back shuttle when the latter is absent, this means preferably being formed as a part of the guide for the back shuttle.

In the present instance I retain in its general form the plunger shown in the aforesaid application, but extend the clips to such a position as 40 will enable them to engage a rear ruled surface of the falling shuttle. The guide means should be preferably movable out of the path of a rear shuttle moving into the compartment, and this result is achieved by associating the guide means 45 with the aforesaid plunger.

A section transverse of the shuttle near the tip thereof will ordinarily be substantially circular but toward the center of the shuttle this section becomes more and more rectangular.

50 55 The means for restraining rotation of the shuttle

should preferably engage the shuttle where its surface is generated by a substantially straight vertical line.

Through failure of the devices already described there is the possibility that a shuttle may enter the transferring shuttle box on the lay with one of its sides down. This might happen also if the operator should inadvertently place one of the shuttles on its side when supplying the stack with fresh shuttles. Under these conditions it 10 would be quite desirable, regardless of the cause of the improperly located shuttle, to prevent the same from being picked out of the box. It is accordingly a further object of my invention to provide a stop on the shuttle box or lay so located 15 as to permit the full sweep of the picker stick, but effective to prevent the shuttle from being delivered from the box. This device may be rendered operative by the fact that the front and back dimension of the shuttle is greater than its 20 height, so that when the shuttle is improperly located on its side the upper edge thereof projects high enough to engage the stop.

By the devices set forth herein assurance is had that an improperly transferred shuttle will 25 not become active, the first of the devices mentioned tending to require the shuttle to move into position correctly, while the stop on the lay acts to prevent delivery of the shuttle should the first devices fail in their operation.

With these and other objects in view, which will appear as the description proceeds, my invention resides in the combination and arrangement of parts hereinafter described and set forth in the claims.

30 35 In the accompanying drawing, wherein a convenient embodiment of my invention is set forth,

Fig. 1 is a detailed transverse section taken through the lower part of the shuttle changer magazine and the upper part of the lay, showing 40 the boxes for effecting shuttle change, a reserve shuttle being shown in the act of delivery from the compartment,

Fig. 2 is a horizontal section on line 2—2 of Fig. 1,

Fig. 3 is a detailed front elevation taken in the direction of arrow 3, Fig. 1, showing diagrammatically the relation of the shuttle boxes and the picking motion,

Fig. 4 is a detailed section on line 4—4 of Fig. 2. 50

Referring to the drawing, I have shown a stationary magazine M having two stacks of shuttles F and R which are respectively at the front and rear of the magazine. A delivery finger 10 is movable about an axis 11 to release the bottom 55

shuttle of the front stack. A clamp 12 acts to engage the shuttle immediately above the bottom one to prevent the descent of the superimposed shuttles of the front stack when the finger 10 moves to the dotted line position shown in Fig. 1.

A plunger head 15 actuated through a rod 16 cooperates with the bottom shuttle of the rear stack and extends through the rear wall 17 of the magazine. A lever 18 pivoted at 19 is actuated by mechanism not shown when it is desired to advance a shuttle from the rear stack to compartment C under the front stack. A light spring 20 serves to return the lever and plunger head to normal rear position.

15 The head 15 has two arms 21 and 22, respectively, each of which has a forwardly and downwardly beveled surface 25, as shown more particularly in Fig. 1. This bevel extends down to a vertical surface 26 on the head located to 20 engage the rear wall of the bottom shuttle in the rear stack.

The two stacks are separated by a partition 30 having a front surface 31 in line with the front of the bottom shuttle of the stack R. The advance movement of the latter shuttle when descending along surface 25 results in this alignment. When so located the shuttle at the bottom of the rear stack will engage the rear surface of a falling shuttle from the front stack and 30 cause the same to move correctly to an upright position, such as indicated in dotted line in Fig. 1.

So long as there is a reserve shuttle in the cell or stack R, the falling front shuttles will be guided as described, but when the rear stack is 35 empty, it is desirable to have additional means to regulate the movements of the front shuttles. This result may be accomplished by the use of a guard 35 which is secured by screws 36 to the plunger head 15. The guard is extended on each 40 side of the head and is bent as shown in Fig. 2 to conform more or less to the shape of the shuttles. The forward ends of the guard are bent toward each other as at 37 to form clips the front edges of which as shown at 38 are substantially 45 vertical to engage the rear wall of the front shuttles at points sufficiently removed from the shuttle tips to prevent shuttle rotation. The bent ends 37 and guide edges 38, as shown in Fig. 2, extend between the rounded ends of the rear and 50 front shuttles when the latter is in the compartment C. The section shown in Fig. 4 illustrates a convenient relation of the holder with respect to that part of a shuttle having a straight vertical surface, the edges 38 lying against the 55 ruled surface 39 of the shuttle.

As shown in Fig. 1, I may provide a front plate 60 which defines the front of the discharge throat or compartment C, and this plate may yield, if desired, as set forth in my aforesaid application Serial No. 460,746.

The guide 35, being mounted on the head 15, moves forwardly with the latter so that the extensions 37 move forwardly with an advancing rear shuttle and do not interfere with it.

65 The lay L may have top and bottom boxes 40 and 41, which as set forth in the aforesaid application, are raised during the shuttle changing operation so that the pivoted cover 42 of the top box can be elevated sufficiently to make a 70 clear passage through the top of the upper box into which the shuttle in the compartment C may fall. Rearwardly extending supporting fingers 43 may be secured to the lay and support the shuttle in the compartment C until the top box arrives 75 in rear position to receive the shuttle. These fin-

gers 43 form no part of my present invention, but are substantially the same in structure and function as those shown in co-pending application Serial No. 560,573.

The matter thus far described operates normally to require a shuttle moving from the magazine into the top box 40 to retain its proper position so that weaving can continue after the shuttle change. If the shuttle enters the box improperly and should rest on its side, weaving can 10 not ensue and it is desirable under these conditions to stop the loom.

I accomplish this result by preventing delivery of the shuttle from the box so that the stop motion not shown but well understood can act due 15 to absence of weft in the shed to stop the loom. The picking operation normally occurs before the filling fork comes into action and in order to prevent breakage of the picker stick it is desirable to place the shuttle arrester so that it 20 will not engage the shuttle until the stick has had its full movement unobstructed.

In carrying out this feature of my invention I place a stop 50 as shown in Fig. 3 on the lay sword 51 so that the lower curved surface thereof 25 is at such a distance above the race 52 as to prevent delivery from the shuttle box of a shuttle which is on its side, but permitting uninterrupted delivery of a shuttle which is properly resting on its bottom. In other words, the distance between the race and the stop 50 is slightly greater than the height of the shuttle but less than its breadth, and is also located about a shuttle length from the inner end of the sweep of the picker stick. The stop 50 is not claimed herein but is made 35 the subject matter of my copending application Serial No. 735,319.

From the foregoing it will be seen that I have provided means for preventing an improperly changed shuttle from becoming active. While 40 the shuttle is in transit from a front cell to the box 40 means are provided either by means of a shuttle in the back cell, or by surfaces independent of the back shuttles, to engage the front moving shuttle and prevent rotation thereof on 45 its axis. Should these fail in their action, however, the stop 50 is provided to prevent the shuttle from being picked into the shed after which well-known stopping mechanism will act to arrest the loom so that the defect may be corrected 50 by the weaver. It will be seen that the means which engage the front shuttle are movably mounted with the plunger head so as not to interfere with forward movement of the rear shuttle; but I do not wish to be limited to this 55 construction inasmuch as it is sufficient for the purposes of the present invention if the guide means are located to direct a shuttle moving from the front stack and are moved out of interfering position with respect to the advanced movement 60 of the rear shuttle.

The stop 50 and the parts related to it to prevent a shuttle on its side from being picked into the shed are claimed in my divisional application Serial No. 735,319.

Having thus described my invention it will be seen that changes and modifications may be made therein by those skilled in the art without departing from the spirit and scope of the invention and I do not wish to be limited to the details 70 herein disclosed, but what I claim is:

1. In a shuttle changing loom, a magazine having two groups of distinctive reserve shuttles and a common delivery throat, a guide located between the groups at one side of the throat to en- 75

gage and prevent turning of a shuttle drawn from one of the groups, and means to move said guide out of the path of the reserve shuttle drawn from the other group which is moving toward changing position.

2. In a shuttle changing loom, a magazine having a front stack and a rear stack of reserve shuttles, means defining a shuttle receiving compartment below the front stack and in front of the rear stack into which reserve shuttles from either stack pass preparatory to shuttle change, an advancer for the shuttles of the rear stack to place them into the compartment, and a guide means on the advancer extending around the ends of a shuttle being moved by the advancer from the rear stack into the compartment, said guide means being extended forwardly toward the path of a shuttle moving from the front stack into the compartment to engage the last named shuttle and prevent the same from turning on its axis.

3. In a multicolor shuttle changing loom, a magazine having a front stack and a rear stack of reserve shuttles, means defining a shuttle receiving compartment below the front stack and in front of the rear stack in which reserve shuttles from either stack pass preparatory to shuttle change, means defining guide surfaces in back of said compartment and in front of the rear stack to engage a shuttle drawn from the front stack and prevent the same from turning on its axis when moving into the compartment, and mechanism to move said means out of the path of the shuttle moving from the rear stack into said compartment.

4. In a shuttle changing loom, a magazine having two stacks of reserve shuttles, a partition between the stacks, means defining a common discharge compartment adjacent both stacks, and means positioned to act upon a shuttle descending in one stack to move the same into substantial alignment with the surface of the partition adjacent the other stack, said means placing the shuttle moved thereby in position to define one side of the compartment to engage a shuttle moving into the compartment from the other stack and to prevent the last named shuttle from turning.

5. In a shuttle changing loom, a magazine having a pair of stacks of reserve shuttles, a compartment common to both stacks and located

under one of them and in front of the other, the shuttles having rounded ends so that a shuttle in the compartment drawn from the stack above the latter defines with the shuttle in the stack behind the compartment a space between the shuttles, and guide means projecting into the space to engage a shuttle drawn from the stack above the compartment as such shuttle moves into the compartment to prevent turning of said last named shuttle.

6. A shuttle advancer for a shuttle changing magazine having a common delivery compartment above which is located one stack of reserve shuttles and behind which is located a second stack of shuttles with a reserve shuttle behind the compartment, said advancer having shuttle guards shaped to conform to and extend around the ends of the shuttle behind the compartment, said advancer having means by which it can be moved to place the shuttle between the guards into the compartment.

7. A shuttle advancer for a shuttle changing magazine having a common delivery compartment above which is located one stack of reserve shuttles and behind which is located a second stack of shuttles with a reserve shuttle behind the compartment, said advancer having shuttle guards shaped to conform to and extend around the ends of the shuttle behind the compartment, and said guards having portions to guide a shuttle moving downwardly into the compartment from the stack of shuttles above said compartment to prevent such shuttle from turning.

8. A shuttle advancer for a shuttle changing magazine having a common delivery compartment above which is located one stack of reserve shuttles and behind which is located a second stack of shuttles with a reserve shuttle behind the compartment, said advancer having shuttle guards shaped to conform to and extending around the ends of the shuttle behind the compartment, and said advancer having a surface positioned and formed to move forwardly a shuttle which is moving toward a position between the guards and cause the front wall of such shuttle to define one side of the compartment located to guide a shuttle falling into the compartment from the first named stack and prevent such last named shuttle from turning.

RICHARD GREENLEAF TURNER. 50
